LEWIS V. MATHER, OF DETROIT, MICHIGAN, ASSIGNOR, BY MESNE ASSIGNMENTS, TO
ENAMELED STEEL PACKAGE CORPORATION, OF AVON, NEW YORK, A CORPORATION
OF NEW YORK.

METAL KEG OR CASK.

1,121,930.

Specification of Letters Patent. Patented Dec. 22, 1914.

Application filed February 18, 1914. Serial No. 819,353.

To all whom it may concern:

Be it known that I, LEWIS V. MATHER, a citizen of the United States, residing at Detroit, county of Wayne, State of Michigan, have invented a certain new and useful improvement in Metal Kegs or Casks, and declare the following to be a full, clear, and exact description of the same, such as will enable others skilled in the art to which it pertains to make and use the same, reference being had to the accompanying drawings, which form a part of this specification.

This invention relates to kegs or casks and has for its object a cask in which the hoops and the head rings are applied to the shell in an improved manner.

This invention is intended as an improvement over the invention shown in the patent of Messrs. Heutteman, Cramer, Weideman, and Schaum, No. 1,086,826 of February 10, 1914.

This invention consists essentially in the utilization of spring tongues on the shell or staves of the cask which spring out and lock with the hoops and the head rings when the latter have been slipped into place.

In the drawings, Figure 1, is a fragmentary view of a cask partly in section. Fig. 2, is a fragmentary perspective of one of the stave-sheaths that form the outer shell. Fig. 3, is a fragmentary view of a modified form of cask shown partly in section. Fig. 4, is a fragmentary perspective of the stave-sheath. Fig. 5, is a fragmentary view of the stave-sheath showing the spring tongue attached to the stave. Fig. 6, is a detail in perspective of the spring tongue.

The cask consists of heat-insulating filler material *a* packed about the inner container *b* and an outer shell *c*. The outer shell *c* is made up of a plurality of sheet-metal stave-sheaths *d*. These sheet-metal stave-sheaths *d* are bound together by metal hoops *e*. These metal hoops *e* are formed with an annular corrugation *f*. The head ring *g* fits over the ends of the stave-sheaths and into the chime of the barrel. This is preferably continued to form the head sheathing *i*. The head sheathing *i* and the head-ring *g* serve to form a cap one of which goes over the end of the barrel. The head ring portion *g* is also provided with an annular outwardly-directed corrugation *j*. These corrugations form recesses into which the spring tongues *k* are adapted to spring when

the hoops and caps have been thrust upon the stave-sheaths and into position. These spring tongues *k* are formed by cutting out a portion of the stave on three sides leaving one side as a hinging axis. This cut-out portion is then drawn into cup-form by forcing the middle of the cut-out portion inward beyond the surface of the stave-sheath. After the stave-sheath has been assembled over the filler material, which is of a compressed nature, the filler material by its springy action always tends to throw the spring tongue outward. When the hoops and the head rings are forced over the staves the spring tongues are temporarily pressed into the filler material, but when the hoops and head rings have been forced far enough upon the staves to bring the recesses formed by the annular corrugations adjacent the tongues, the tongues spring into the recesses formed by the annular corrugations and permanently lock the hoops and the head rings in position.

In Figs. 3 to 6 inclusive I have shown a modified form in which a separate plate *l* is used as a spring tongue. This plate *l* is a curved plate, as shown in Fig. 6. It is provided with a pair of struck-out ears *m*. The depression *n* is made in the surface of the stave by a suitable die, but the lugs *o* are cut out of the metal forming this depression and are left almost flush with the main surface of the stave at the top of the depression. These lugs *o* are adapted to be bent over the ears *m* of the spring plate (see Fig. 5) to hold the plate in place. The spring plate or tongue *l* is slipped into the depression and the ears *m* will register with the lugs *o*. The ears and the lugs can be omitted and the spring plate spot-welded to the stave-sheath. The original curvature of the plate tends to throw the spring tongue out as shown in Fig. 3. However, inasmuch as the plate and the spring tongue *l* are made of thin metal, when the hoops and the cap rings are forced upon the staves the spring tongue or plate *l* are temporarily forced into the depression *n* until the hoops and the head rings have been forced far enough on the stave-sheaths to bring the annular recesses adjacent the spring plates, whereupon the spring tongue or plates *l* will immediately spring out and engage in the annular recesses. This permanently locks the hoops and the cap rings.

in place. Were any effort made to shift the hoops or cap rings toward the end of the cask it will be tensilely resisted by the spring plates or tongues *l* backed by the 5 upper wall of the depression. Each stave-sheath is preferably supplied with one of these spring tongues. This form of a lock has the advantage of being both permanent and being invisible in the completed cask.

10 Referring to the "spring tongues" in the claims, the term is used in a broad sense to include not only a tongue such as *k* but also plates such as *l* and any other projecting element which would properly come within 15 the designation.

What I claim is:

1. A cask, having in combination, a container, filler material thereabout, an outer sheathing about the filler material and having metallic portions provided with hinged tongues that by reason of their hinging action may be pressed from a position of projection with respect to the outer sheathing to a position interior of the outer surface of the outer sheathing, and a ring or band member for fitting over the outer sheathing and provided with an inwardly opening recess whereby the band may be 20 25

slipped over the outer sheathing and the hinged tongues which are temporarily 30 pressed out of projecting relation with respect to the sheathing to allow the said ring or band to pass over them and which subsequently spring back into the recess of the band or ring to lock the same to the 35 sheathing.

2. A cask, having in combination, a container, filler material thereabout, an outer sheathing inclosing the filler material and provided with a plurality of tongues, each 40 of which is fixed at one edge with respect to the sheathing and which is free at all the other edges, the said tongues being arranged to normally project from the face of the sheathing, but being capable of being forced 45 below the surface of the sheathing, and a band or ring fitting over the outer sheathing and having an inwardly opening recess into which the tongues spring when the recess is brought into registry with the same. 50

In testimony whereof, I sign this specification in the presence of two witnesses.

LEWIS V. MATHER.
